OTHER PUBLICATIONS

Atlas Copco "RTX Series Hydraulic Torque Wrench" datasheet
dated Jun. 2015.

Primary Examiner — Austin Murphy

(74) *Attorney, Agent, or Firm* — Young Basile Hanlon &
MacFarlane, P.C.

(57) **CLAIM**

The ornamental design for a hydraulic torque wrench as
shown and described.

DESCRIPTION

The patent or application file contains at least one drawing
executed in color. Copies of this patent or patent application
publication with color drawing(s) will be provided by the
Office upon request and payment of the necessary fee.

1.1 : Left front perspective

1.2 : Back

1.3 : Front

1.4 : Top

1.5 : Bottom

1.6 : Left

1.7 : Left rear perspective

1.8 : Right

No protection is sought for the matter shown in ghost lines
and without shading.

**1 Claim, 8 Drawing Sheets
(6 of 8 Drawing Sheet(s) Filed in Color)**
